UNITED STATES PATENT OFFICE.

CHARLES H. TURNER, OF WORCESTER, MASSACHUSETTS, ASSIGNOR TO OSGOOD BRADLEY CAR COMPANY, OF WORCESTER, MASSACHUSETTS, A CORPORATION OF MASSACHUSETTS.

CAR-VENTILATOR.

1,245,826.

Specification of Letters Patent.

Patented Nov. 6, 1917.

Application filed May 26, 1916. Serial No. 100,128.

To all whom it may concern:

Be it known that I, CHARLES H. TURNER, a citizen of the United States, residing at Worcester, in the county of Worcester and 5 State of Massachusetts, have invented a new and useful Car-Ventilator, of which the following is a specification.

This invention relates to a ventilator particularly adapted for use on passenger cars. 0 It is essential that such ventilators be effective to induce a brisk circulation of air therethrough, and also that they positively prevent entrance of rain or snow under all conditions of wind or weather.

15 Many of the usual types of ventilators fail to give satisfaction in this latter respect, as they do not adequately protect the passengers from moisture under certain conditions, and particularly when hard driving 20 storms are accompanied by high winds.

It is the object of my invention to improve the construction of such ventilators to the end that they may more effectively perform their office and that they may afford 25 absolute protection to the passengers.

With this general object in view my invention relates to certain arrangements and combinations of parts which will be hereinafter described and more particularly 30 pointed out in the appended claim.

A preferred form of my invention is shown in the drawings in which—

Figure 1 is a perspective view of my improved ventilator;

35 Fig. 2 is a vertical sectional view taken along the line 2—2 in Fig. 1, and

Fig. 3 is a transverse sectional view taken along the line 3—3 in Fig. 1.

The ventilator shown in the drawings is 40 of a twin or double form and is shown mounted upon the roof 10 of a passenger car. A circular sleeve or intake 11 is inserted in the roof of the car, and may be provided with a perforated cover 12 at its lower end. The intake communicates with lateral passages 13—13 which extend in opposite directions to the two separate outlet portions. The plate 14 which covers the lateral passages 13 may be reinforced by a 45 rib 15 on its lower side, if so desired.

50 At their outer ends the passages 13 communicate with inner vertical flues 16 which extend upward therefrom, and are covered by caps 17. These caps are spaced from the 55 upper ends of the flues 16 both vertically

and laterally, and the edge portions of the caps extend downward below the upper edges of the flues 16.

The caps 17 are inclosed within outer vertical flues 18, and the space between each 60 cap 17 and flue 18 is filled in with an open grille work or grating 19. This grille work serve to support the cap and to hold the same in the correct relation to the flues 16 and 18. The grille work is formed of vertical 65 members having substantially the same depth as the edges of the cap 17, thus subdividing the outer flue into a plurality of separated passages of comparatively small cross section. This subdivision of the flue 70 materially increases the effectiveness of ventilators of this type, as is well known in the art.

The circulation of the air through my improved ventilator is clearly shown by the 75 small arrows in Figs. 2 and 3. It will be seen that the air rising through the intake 11 passes to the right or to the left along the lateral passages 13 from which it passes upwardly through one of the inner flues 16, 80 then downwardly between the flue 16 and the cap 17, and finally upward through the grille work 19 to the open air.

With this construction it is absolutely impossible, under any conditions of weather, 85 for rain or snow entering through the grille work 19 to reach the interior of the car. Whatever moisture enters through the grille work collects within the outer flue 18 and is taken care of by drainage openings 20 (Fig. 1) at the lower outer edge of the flue 18. The partition 21 which closes the outer 90 end of the passages 13 is slanted sharply downward, as shown in Fig. 2, to conduct the drainage to the openings 20.

Having thus described my invention it will be seen that this ventilator is of a compact and serviceable form and that the air currents are so directed that moisture will be absolutely excluded from the interior of 100 the car. While I have shown a double or twin ventilator, it will be understood that the advantages of my invention may be equally well secured in a single ventilator such as would be produced by inserting a 105 partition 22 in the device shown in Fig. 2, and omitting the construction shown to the right of said partition.

It will be evident that other changes and 110 modifications can be made in my invention

without departing from the spirit and scope thereof as set forth in the claims, and I do not wish to be otherwise limited to details herein disclosed, but what I claim is:—

- 5 A car ventilator comprising an inner vertical flue, a cap supported above said flue and inclosing the upper end thereof, said cap being spaced from said flue both vertically and laterally and having its edge portion extending below the upper open end of said flue on all sides thereof, an outer vertical flue surrounding said cap and inner flue, and held in fixed spaced relation to
- 10

said cap by a grille work interposed between the cap and the outer flue and secured to each of said members, and an imperforate bottom plate connecting said inner and outer flues at their lower ends, portions thereof being outwardly and downwardly inclined and said outer flue having drainage openings near the lower outer edge thereof. 15 20

In testimony whereof I have hereunto set my hand.

CHARLES H. TURNER.
